UNITED STATES PATENT OFFICE.

EZRA B. SMITH, OF CHICAGO, ILLINOIS, ASSIGNOR TO THE J. G. WILSON CORPORATION, OF NEW YORK, N. Y., A CORPORATION OF VIRGINIA.

LOCKING DEVICE FOR FOLDING PARTITIONS.

Application filed September 15, 1925. Serial No. 56,434.

This invention relates to folding partitions or doors which are arranged to slide along suitable guideways or tracks across a door opening, and also to swing with relation to the guideways into positions substantially perpendicular to the plane of the door opening.

As is well known to those skilled in the art, it is highly important that the doors of the folding partition when in folded position shall be locked securely from sliding movement along the tracks in either direction. The doors at points adjacent the track when folded should be held firmly in spaced relation and should also be locked from bodily sliding movement in a direction away from that side of the doorway adjacent to which the doors are folded. This insures a normal regular unfolding of the doors in succession during the closing operation and eliminates danger of jambing and breakage of the parts which often occurs when the doors are not properly locked in position. The doors should be locked in position upon folding the same as soon as they start to fold and should be maintained in locked condition while folded and during the unfolding operation until just before the doors are swung into the plane of the doorway in position to slide along the tracks.

The principal objects of the present invention are to improve the construction and mode of operation of the locking devices for locking the doors of a folding partition from movement along the track or tracks when in folded positions, and to provide a construction which will operate to lock the doors during the first part of the folding movement thereof and to unlock the doors during the last part of the unfolding movement thereof.

With the above objects in view, the invention comprises the novel and improved features, constructions and combinations of parts hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings—

Fig. 1 is a view in front elevation illustrating a folding partition embodying the invention with the doors thereof in closed position;

Fig. 2 is a view in horizontal section of the partition with certain of the doors in folded positions and certain of the doors in partially folded position;

Fig. 3 is a view in vertical section taken substantially on the line 3—3 of Fig. 1;

Fig. 4 is a view in vertical section illustrating the devices shown in the upper part of Fig. 3 with certain parts in different positions;

Fig. 5 is a detail view in side elevation illustrating certain of the locking devices for locking the doors;

Fig. 6 is a view in horizontal section of the partition structure taken substantially on the line 6—6 of Fig. 7;

Fig. 7 is a view in front elevation of the structure shown in Fig. 6 with certain parts broken away;

Fig. 8 is a view partly in front elevation and partly in vertical section illustrating the devices for guiding the lower portions of the doors and for locking certain of the doors in position;

Fig. 9 is a view in horizontal section taken substantially on the line 9—9 of Fig. 8;

Fig. 10 is a view in horizontal section illustrating the mode of operation of the locking devices shown in Figs. 8 and 9;

Fig. 11 is a view similar to Fig. 8 illustrating a modified form of the locking devices for locking the lower portions of certain of the doors;

Fig. 12 is a view in horizontal section illustrating the mode of operation of the locking devices shown in Fig. 11;

Fig. 13 is a diagrammatic view illustrating

ing certain parts of the locking mechanism and certain co-operating devices, and

Fig. 14 is a view similar to Fig. 13 illustrating certain of the parts in different positions.

The folding partition in which the invention is embodied as illustrated in the drawings of this application comprises a series of doors hinged together in pairs to form 10 partition sections. The door at one end of the partition is pivoted to swing upon a fixed vertical axis, while the other doors of the partition are mounted for sliding and swinging movement in upper and lower guideways 15 or tracks extending across the doorway.

Each section of the partition comprises doors 1 and 2, these doors being hinged together by means of hinges 6 to swing with relation to each other. The left end door 1 20 of the partition, Fig. 1, is pivoted to swing upon upper and lower pivot bolts or studs 8 engaging in suitable bearings in the door frame. Thus this door is anchored to swing about a fixed vertical axis. The doors are 25 guided at their upper margins by means of rollers 9 rotatably mounted upon fixed studs 10 secured in the doors, the rollers engaging the sides of a U-shaped track or guideway 12 secured in a frame 14 at the upper margin 30 of the doorway. The track 12 is supported upon angle plates 16 secured to the frame 14.

The doors are guided at their lower margins by means of casters 18 running upon a suitable track 20. The casters 18 are journaled upon a bracket or hanger 22 secured to the lower end of a caster bolt 24 mounted for longitudinal and rotative movement in a frame 26 secured in the lower margin of the door. The bracket 22 carries a guiding 40 projection or plate 28 which engages in a groove 29 in the track 20 and guides each door in the direction of the track and also prevents the caster bolt from rotating during the pivotal movement of the door. Each 45 of the caster bolts is provided with a spring 30 interposed between a collar on the bolt and a crosspiece on the frame 26 which maintains the casters 18 at all times in contact with the track, thus compensating for 50 any unevenness in the track which might tend to lift the casters from the track. The upward movement of the caster bolt in the frame 26 is limited by an adjustable abutment screw 32 with which the upper end of 55 the caster bolt engages.

Preferably the doors 2 of each section except the left-hand section are respectively provided with pins 31 which engage in the upper guideway and hold the doors of a 60 section in extended position in substantially the same plane except when the section has been slid along the guideways to folding position at one side of the doorway. The upper guideway frame 14 and the associated 65 devices are formed with a slot 33 with which

the respective pins 31 register when the corresponding sections are moved into folding position, this slot being arranged to receive the respective pins 31 as the several sections are folded.

In order to lock the doors from movement along the guideway, in the present embodiment of the invention, devices are provided for locking both the upper and lower margins of the doors. These locking devices 75 are applied to the door of each section nearer that side of the doorway adjacent to which the sections are folded except the door of the section which is folded. The door 1 of the latter section is anchored in position by 80 the pivot bolts 8 and has only a pivotal movement.

The locking devices for the upper margin of each of the doors 1 comprise locking dogs 34 and 35 secured to a plate 36 which is pivoted to turn on the stud 10 on which the roller 9 is journaled. These dogs are arranged to engage respectively the teeth of rack bars 38 and 40 secured to the angle plates 16 within the upper guideway. The 90 dog 34 when engaged with the rack 38 will lock the door 1 from movement along the guideway in a direction away from the previously folded sections while the dog 95 when engaged with the rack 40 will lock the door 1 from movement along the guideway in a direction toward the previously folded sections.

The dogs are acted upon by a coiled 100 spring 42 which tends to carry the same into engagement with the respective racks 38 and 40. The dogs are held out of engagement with the racks by a pin 44 mounted on the door 1 and arranged to engage the dog 34 as shown in Fig. 6.

The extreme right-hand door 1 is shown in Fig. 6 in unfolded position with the dogs 34 and 35 held out of engagement with racks 38 and 40 by the pin 44. As a section is folded, the swinging of the door 1 of the 110 section carries the dogs into engagement with the racks during the first part of the folding movement, thereby locking the door from sliding movement in either direction along the guideway. During the continued 115 swinging movement of the door 1, after the dogs engage the racks, the spring 42 yields and the dogs are held thereby firmly in engagement with the racks. As the section is unfolded, the door 1 is held from sliding 120 movement along the guideway until the last part of the unfolding movement, when the pin 44 engages the dog 34 and disengages the dogs from the racks.

The locking devices for the lower margins 125 of the doors 1 are similar in construction and mode of operation to the devices for locking the upper margins of the doors. In the construction shown in Figs. 8, 9 and 10, the locking devices for the lower margins 130

of the doors comprise locking dogs 46 and 48 mounted upon a common carrier 50 pivoted upon the caster bolt 24. These locking dogs are arranged to engage respectively in 5 notches 52 and 54 formed in the sides of the groove 29. The engagement of the dog 46 in the notch 52 will lock the door 1 from movement along the track in a direction toward the previously folded doors, while the 10 engagement of the dog 48 in the notch 54 will lock the door from movement in the opposite direction along the track.

The carrier 50 is acted upon by a coiled spring 56 which tends to swing the same in 15 a direction to carry the locking dogs into engagement with the notches in the groove 29. The dogs are held out of engagement with the notches when the doors of a section are in unfolded position by means of a pin 20 58 mounted in the frame 25 and engaging the dog 48, as shown in Figs. 8 and 9.

During the folding of a section, the dogs 46 and 48 are carried into locking engagement with the locking notches 52 and 54 25 during the first part of the folding movement of the section, are held in engagement with the notches while the section is folded, and are disengaged from the notches during the last part of the unfolding movement of 30 the section in substantially the same manner that the dogs 34 and 35 are engaged with and disengaged from the racks 38 and 40 as described above.

In the construction shown in Figs. 11 and 35 12, the locking dogs have substantially the same construction, arrangement and mode of operation as the locking dogs shown in Figs. 8, 9 and 10, except that the dogs shown in Figs. 11 and 12 do not extend into the 40 groove 29 but are located above the track to swing over the same and are arranged to engage in notches 60 and 62 formed respectively in blocks 64 and 66 secured to the floor alongside the track. As shown in Fig. 45 12, the blocks 64 and 66 are located outside of the path of the casters 18, so that they will not interfere with the sliding movement of the doors.

In the construction shown in Figs. 8, 9 50 and 10, and also in the construction shown in Figs. 11 and 12, the carrier 50 for the locking dogs is held in engagement with a shoulder on the bracket 22 secured to the locking bolt so that the dogs are maintained in a constant vertical position with relation 55 to the caster bolt and to the track.

The pin 31 on each of the doors 2 of the right hand and central sections of the partition, together with the slot 33 determine the 60 point in the guideways at which these doors may be locked and prevent them from being locked in the wrong position. These doors thus can be turned into locking position only when the locking devices at the bottom 65 of the doors are in position to engage the

corresponding locking devices along the lower track.

The locking devices are preferably arranged to maintain the doors to which they are applied in locked condition until the pin 70 31 passes inwardly through the slot 33 and enters the upper guideway as shown in Fig. 13 during the unfolding of a section. The locking devices thus will prevent movement of the sections along the tracks until the 75 doors thereof are substantially completely unfolded and ready for trackwise movement. The door 1 of a section cannot be locked during the folding of the section until the pin 31 mounted thereon enters the 80 slot 33. Thus the door cannot be locked except when the pin 31 is in position to engage in the slot 33. The co-operation of the locking device and pins 31 together with slot 85 33 will prevent the doors of a section from being slid along the guideways while the pin 31 on said section is located outside the frame 14 as often happens with other constructions and also insures the locking of the doors at the proper point in the guideway.

With the above construction, the door 1 of each section of the partition will be locked firmly in position against sliding movement along the track during the folding operation 90 substantially as soon as the section starts to fold and will be maintained in locked condition while the section is completely or partially folded. The locking devices at the upper and lower margins of each of the doors 1 100 will lock the said doors from movement toward the previously folded doors, thereby maintaining the doors in proper spaced relation, and will also lock the doors from movement in the opposite direction along 105 the tracks. In the unfolding operation, the doors 1 will be maintained in locked condition until just before the two doors of a section are swung into alignment and into the central plane of the doorway. The 110 doors will then be unlocked and are free to slide in the plane of the doorway along the upper and lower tracks in the usual manner.

The locking devices may be actuated to lock the doors during the first 10° or even 115 less of the initial swinging movement of the doors in folding same, and to unlock the doors during the last 10° or less of the swinging movement during unfolding.

It is to be understood that the invention 120 is not limited to the particular construction and arrangement of parts of the illustrated embodiment of the invention, but that the invention may be embodied in other forms within the scope of the claims.

Having explained the nature and object 125 of the invention and having specifically described a construction embodying the invention in its preferred form, what is claimed is:

1. A folding partition construction com- 130

- prising hingedly connected doors, a guideway along which the doors are arranged to slide and locking devices for locking one of the doors from movement in either direction 6 along the guideway when the doors are folded, constructed and arranged to operate to lock said door during the first part of its folding movement and to unlock the doors during the last part of the unfolding movement thereof. 11 7. A folding partition construction comprising a guideway, a door mounted for sliding and swinging movement along the guideway, oppositely acting locking dogs connected yieldingly with the door for locking the door from movement along the guideway when the door is folded, constructed and arranged to lock the door during the first part of its folding movement and to unlock the same during the last part of its unfolding movement, and rack bars on opposite sides of the guideway for engagement with the locking dogs to lock the door. 75
2. A folding partition construction comprising a guideway, a door mounted for sliding and swinging movement along the guideway and locking devices for locking the door 15 from movement in either direction along the guideway when the door is folded, constructed to lock the door during the first part of its folding movement and to unlock the door during the last part of the unfolding movement thereof. 20 8. A folding partition construction comprising a guideway, a door mounted for sliding and swinging movement along the guideway, a dog yieldingly connected with the door for locking the door from movement along the guideway when the door is folded and a ratchet arranged to be engaged by the dog to lock the door. 80
3. A folding partition construction comprising a guideway, a door mounted for sliding and swinging movement along the guideway, a locking dog pivotally connected with 25 the door adjacent the axis upon which the door swings, means mounted alongside the guideway for engagement with the dog to lock the door from movement along the guideway, a spring tending to swing the dog with relation to the door into engagement with said means and, a stop on the door arranged to engage the dog to hold the dog out of engagement with said means when the door is in position to slide and to allow the 30 dog to engage said means when the door is folded. 90
4. A folding partition construction comprising a guideway, a door mounted for sliding and swinging movement along the guideway and locking devices for locking the door from movement in either direction along the guideway, constructed and arranged to lock the door during the first part of its folding movement. 40 9. A folding partition construction comprising a guideway, a door mounted for sliding and swinging movement along the guideway, a locking dog yieldingly connected with the door for locking the door from movement along the guideway when the door is folded, means yieldingly engaged by the locking dog to lock the door in position when the door is swung out of the plane of the doorway, and a device for disengaging the dog from said means when the door is swung back into the plane of the doorway. 95
10. A folding partition construction comprising in combination a frame having a guideway and a slot leading to the guideway, a door mounted for sliding and swinging movement, a pin mounted on the door for engaging in the guideway during the sliding movement of the door and arranged to pass through the slot during the swinging movement of the door and locking means arranged to hold the door locked against sliding movement while the door is wholly or partially folded and to hold the door unlocked while in unfolded condition and until the pin enters the slot at the beginning of the folding movement of the door. 100
11. A folding partition construction comprising in combination a frame having a guideway and a slot leading to the guideway, a door mounted for sliding and swinging movement, a pin mounted on the door for engaging in the guideway during the sliding movement of the door and arranged to pass through the slot during the swinging movement of the door and a movable locking device arranged to lock the door from sliding movement along the guideway as soon as the pin is swung out of the guideway during the folding movement of the door and arranged to maintain the door in locked condition until the pin is swung back into the guideway during the unfolding movement of the door. 115
12. A folding partition construction comprising a guideway, a door mounted for sliding and swinging movement along the guideway and two oppositely acting locking dogs for locking the door from movement in either direction along the guideway when the door is folded, constructed and arranged to lock the door during the first part of its folding movement and to unlock the same during the last part of its unfolding movement, and means co-operating with the respective dogs to lock the door. 120
13. A folding partition construction comprising a guideway, a door mounted for sliding and swinging movement along the guideway, a locking dog yieldingly connected with the door for locking the door from movement along the guideway when the door is folded, means yieldingly engaged by the locking dog to lock the door in position when the door is swung out of the plane of the doorway, and a device for disengaging the dog from said means when the door is swung back into the plane of the doorway. 125
14. A folding partition construction comprising in combination a frame having a guideway and a slot leading to the guideway, a door mounted for sliding and swinging movement, a pin mounted on the door for engaging in the guideway during the sliding movement of the door and arranged to pass through the slot during the swinging movement of the door and a movable locking device arranged to lock the door from sliding movement along the guideway as soon as the pin is swung out of the guideway during the folding movement of the door and arranged to maintain the door in locked condition until the pin is swung back into the guideway during the unfolding movement of the door. 130

12. A folding partition construction comprising in combination upper and lower guideways, a door mounted for sliding and swinging movement along said guideways, 5 locking devices mounted on the bottom of the door and arranged to be thrown into operation by the folding movement of the door, co-operating locking devices arranged along the lower guideway, a pin mounted on the top of the door and devices co-operating with the pin to cause the registration of the locking devices on the bottom of the door with the co-operating locking devices along 10 the lower guideway before the door can 15 swing into locking position.

13. A folding partition construction comprising in combination a guideway, a door mounted for sliding and swinging movement along the guideway and a locking device 20 yieldingly connected with the door and actuated by pivotal movement thereof from locking the door against movement along the guideway.

14. A folding partition construction comprising in combination a guideway, a door mounted for sliding and swinging movement along the guideway, a locking device 25 movably mounted on the door for locking the door against movement along the guideway 30 when the door is swung out of line with the guideway and means actuated by the swinging movement of the door for controlling the locking device.

15. A folding partition construction comprising upper and lower tracks, a door mounted for sliding and swinging movement along said tracks and locking means 35 for locking the base of the door from movement in either direction along the lower track when the door is swung out of line with the tracks.

16. A folding partition construction comprising upper and lower tracks, a door mounted for sliding and swinging movement along said tracks and locking means 45 carried by the base of the door and cooperating locking devices on opposite sides of the lower track for engagement with said locking means when the door is swung out of line with the tracks for locking the base of the door from movement in either direction along the lower track.

17. A folding partition construction, comprising in combination a grooved lower 55 track, a door mounted for sliding and swinging movements along said track, a locking device mounted on the door to yield with relation to the door and engaging in the groove of said track, and a cooperating fixed 60 locking device mounted in the groove and arranged to be engaged by said first locking device when the door is swung into folded position to lock the door from movement along the track.

18. A folding partition construction com-

prising in combination a guideway, a door mounted for sliding and swinging movements along the guideway, a pivot upon which the door is arranged to swing during the folding movement thereof, and a locking device pivotally mounted to turn relatively to the door on said pivot and actuated from the door as the door is swung into folded position for locking the door from movement along the track. 70 75

19. A folding partition construction comprising in combination a guideway, a door mounted for sliding and swinging movements along the guideway, a pivot about which the door is arranged to swing during the folding movement thereof and a locking dog pivoted on said pivot to swing relatively to the door and arranged to lock the door from movement along the track as the door is swung into folded position. 80 85

20. A folding partition construction comprising in combination a guideway, a door mounted for sliding and swinging movements along the guideway and a locking dog pivotally mounted on the door and 90 yieldingly connected therewith for locking the door from movement along the guideway when the door is folded.

21. A folding partition construction comprising in combination an upper guideway, 95 a door mounted for sliding and swinging movements along the guideway, a stud mounted on the door, an anti-friction device pivotally supported on the stud and engaging the sides of the guideway, and a locking device pivoted on the stud to swing 100 relatively to the door for locking the door from movement along the guideway when the door is folded.

22. A folding partition construction comprising in combination a lower track, a door mounted for sliding and swinging movements along the track, a caster bolt attached to the lower margin of the door, one or more casters mounted on the caster bolt to 110 turn on substantially horizontal axes and resting on the track and a locking device pivoted on the caster bolt for locking the door from movement along the guideway when the door is folded. 105 115

23. A folding partition construction comprising a lower grooved track, a door mounted for sliding and swinging movements along the track, a pivoted locking dog mounted on the door to swing relatively to the door in a plane substantially parallel with the plane of swinging movement of the door and engaging in the groove in said track, and cooperating devices mounted within the groove in the track and arranged 120 to be engaged by the locking dog to lock the door from movement along the track when the door is folded. 125

24. A folding partition construction comprising in combination a lower grooved 130

track, a door mounted for sliding and swinging movements along the track, oppositely acting pivoted locking dogs mounted on the door to swing relatively to the door in a plane substantially parallel to the plane of swinging movement of the door and engaging in the groove in the track, and devices

mounted in said groove on opposite sides thereof for engagement respectively by said locking dogs to lock the door from movement along the track when the door is in folded position. 10

Signed at New York, N. Y., Aug. 20, 1925.
EZRA B. SMITH.
